GAME

John L. Zinngrabe, Chicago, Ill.

Application December 4, 1937, Serial No. 178,032

5 Claims. (Cl. 273—85)

This invention relates to games in general and particularly to a table game to be played by two or more persons constituting opposing sides.

An important object of the invention is to provide a new, fascinating and extremely interesting game of skill in which quickness of thought and muscle co-ordination are required to advance or retard an element from one end zone to another end zone.

Another object is the provision of a new arrangement and assembly of parts constructed in a particular manner so as to form a neat and efficient apparatus whereby a playing element may be moved over a playing surface toward certain end zones.

A still further object of the invention is to provide a game whereby a frame has a flexible, resili- 5 ent, rubber or rubberlike material arranged over the frame to constitute the playing surface, there being operating members arranged beneath the playing surface to be operated or controlled by the fingers of the players whereby a playing element may be moved toward or away from certain end zones according to the position of the element and the manner in which the players cause the element to be moved.

Numerous other objects and advantages will be apparent throughout the progress of the following specification.

The accompanying drawings illustrate a selected embodiment of the invention and the views therein are as follows:

Fig. 1 is a top plan view of the improved game;

Fig. 2 is a longitudinal sectional view on the line 2—2 of Fig. 1;

Fig. 3 is a top plan view, the top cover or playing surface being removed;

Fig. 4 is an isometric view showing some of the operating mechanism in rest position;

Fig. 5 is a similar view showing some of the operating mechanism in advanced or operating position;

Fig. 6 is a detail perspective view showing certain elements representative of a goal, the parts being shown in normal or rest position;

Fig. 7 is a view similar to Fig. 6 but showing the parts in advanced or operating position; and

Fig. 8 is a detail perspective view of one of the operating elements.

The particular game apparatus herein shown for the purpose of explaining the invention is intended to imitate closely the association game of hockey, the game being played with a small ball or marble to imitate a puck. The game apparatus has a surface upon which the puck is

moved and is provided with goals like a hockey field. The various phases of the hockey game are carried out by the manipulation of certain elements or men to advance the puck (ball or marble) toward an end zone or goal. The playing surface is marked with certain indicia or identifications which represent the playing position of the various players on the field. The field itself constitutes a sheet of elastic or rubberlike material mounted on a base or frame. Underneath this playing surface or field there is arranged a plurality of elements or men which are manually manipulated and indicate the hockey players and their position on the field. The indicia indicating the men comprise colored spots or marks so that the position of the elements or men underneath the table may be readily determined. Therefore, when the puck arrives at a position or approximately at a position where a man is located, the man can be manually operated. The players, therefore, know the position of the elements or men at all times. These men are arranged beneath the playing surface and are so controlled and constructed so as to cause the puck to be driven away from the opponent's goal. The game is adapted to be played by two or more players constituting opposite sides, and the players manually operate the men from the respective ends of the game and actuate the men so as to cause the puck to be moved toward the opponent's goal. The opponent, however, also operates mechanism so as to operate the men to prevent the puck from entering the goal.

The game, therefore, is arranged to imitate a hockey game. However, other amusing games as well as imitation hockey may be played on the same apparatus.

The game apparatus comprises a casing or support 1 having a base or bottom board 2 upon which end members 3 and 4 and side members 40 or rails 5 and 6 are suitably mounted. The end members 3 and 4 are spaced inwardly from the outer ends of the base 2 to provide hand supports or rests 7 and 8.

A frame 9 is arranged within the framework 45 of the casing 1 and comprises side members 10 and 11 and end members 12 and 13. The end members 12 and 13 of the frame 9 are spaced inwardly of the exterior casing end members 3 and 4, respectively, to provide spaces to accommodate other mechanism which will later be described, Figs. 2—5. This frame 9 is fixed to the base 2 in any suitable manner such as by gluing or nailing and may include diagonal corner braces 14, Fig. 3, to strengthen the frame.

A plurality of elements 15, herein termed men, are mounted on the upper surface of the base 2, Figs. 2-5, and each element or man 15, Fig. 8, comprises a base portion 16 which is adapted to be fastened to the base 2. Upstanding arms 17 are rigidly connected to the base portion 16 and revolvably support a semi-cylindrical member or rocker 18 which is mounted for rotation or oscillation on a shaft or pin 19 which passes through the leg 17 and through the rocker operating member 18. A ball or other striking element 20 is connected to a rod or bar 21, the bar having its other end fixed to the rocker element 18 as indicated at 22, Fig. 8. A string, cord, thread, wire, or like operating member 23 is fixed to the rocker element 18 as indicated at 24 and extends partly around the semi-circular rocker member 18, fitting into a circumferential groove 25. A guide eye 26, Fig. 8, may be fastened to the base portion 16 of the member 15 so as to assure the string 23 being properly positioned with respect to the semi-annular groove 25 in the rocker element 18.

Four of the men 15 are fastened to the base 25 at the positions indicated at A, B, C, and D, Figs. 1 and 3, and are connected by cords 23 to operating levers or plungers 27. For convenience, the operating levers 27 which control the men at the points designated A, B, C, and D will be numbered 27A, 27B, 27C, and 27D, respectively. These plungers are located at the left hand side of the board and are adapted to be operated by the fingers of the left hand.

Each operating lever or plunger may be of 35 any construction and may have any type of a spring co-operating therewith to maintain it in a predetermined position. However, in the present embodiment it is shown as being relatively U-shaped, Figs. 4 and 5, one end being provided 40 with an eye 28, Figs. 4 and 5, and its other end provided with a bent portion 29 which acts as a stop to limit the outward pull. A spring 30, Figs. 4 and 5, is arranged between the end member of the outer framework 1 and the end member of the inner frame 9, and is adapted to urge 45 the member 27 inwardly, as shown in Fig. 4, there being a stop 31 fixed to the member 27 to limit the inward movement of the operating lever or plunger 27. The spring 30 may have one of its 50 ends fixed to the stop 31 if desired and its other end provided with a loop to permit free slideable movement of the leg of the operating member or lever 27 to which the spring is connected. Therefore, inward movement of the lever is restricted 55 by the stop 31, while outward movement is limited by the leg or extension 29.

Four other men 15 are fastened to the base 2 at the positions indicated at E, F, G, and H, and are connected by cords 23 to their respective 60 operating levers or plungers 27E, 27F, 27G, and 27H. The operating levers or plungers 27E, 27F, 27G, and 27H are located on the same side as the plungers 27A, 27B, 27C, and 27D, and are adapted to be operated by the same player but 65 with the fingers of the right hand. The positions A, B, C, and D are relatively close to the player who sits at the left, Fig. 1, while the positions E, F, G, and H are positioned toward the opposite end near the opponent's goal.

70 The other side of the apparatus also has plungers or operating levers 27K, 27L, 27M, and 27N which are operated by the fingers of the left hand of the opponent and control the men located at positions K, L, M, and N. The positions 75 K, L, M, and N on the right hand side, Fig. 1,

correspond identically with the positions A, B, C, and D on the left hand side of Fig. 1. Also, the operating plungers or levers 27O, 27P, 27Q, and 27R which are operated by the fingers of the right hand of the opponent control the men located at positions O, P, Q, and R. The positions O, P, Q, and R on the right hand side of Fig. 1 correspond identically with the positions E, F, G, and H on the left hand side of Fig. 1.

The same fingers, therefore, of opponents operate the men in the same positions but on opposite sides, so that when the little finger of the player on the left hand side of Fig. 1 operates lever 27A, the little finger of the left hand of the opponent on the right hand side of Fig. 1 will operate 27K. Likewise, the other fingers of the hands operate similar men at the similar positions.

A flexible sheet 32 of rubber or rubberlike material or any other material that is yieldable to 20 form the playing field is arranged over the men 15 and stretched taut but not tight over the top of the frame 9, being held in position by side strips 33, Figs. 1 and 2, and end strips 34, Figs. 2, 4, and 5. These strips 33 and 34 are preferably 25 removable, being held by screws, so that a new sheet or field may be quickly and easily attached. Also, end pieces 35 may be mounted on the upper surface of the frame 1, being inclined at 36, so that the inclined edge 36 will be above the under-braces 34. The inclined edges 36 slope toward the center toward openings 37 at each end, which openings represent and constitute the goal through which a ball or marble 38, Figs. 4 and 5, constituting a puck, may fall during play. The 35 player getting the puck into the opponent's goal, that is, causing the marble 38 to fall through the opening 37 at the opponent's end, scores a goal which constitutes a point, in the same way in which hockey is played.

The game apparatus further provides for a 40 goalie, and this goalie is represented by the numeral 39, Figs. 6 and 7, and constitutes a flat strip or plate 40 having openings 41 formed therein. The strip 40 bridges the opening 37 so as to 45 restrict the puck from getting into the goal zone. However, if the puck enters the openings 41, a goal will be scored. The goalie is adapted to be operated by striking a plunger 42. The plunger 42 is pivotally connected at 43 to a strip 44 which 50 may be integral with the plate 40, Fig. 5. An integral portion 45 connects the portions 43 and 44 which are offset from each other, as clearly shown in Figs. 6 and 7. The member 39 is hingedly connected to a part of the frame 9 and is urged outwardly, as shown in Fig. 6, by means of a spring 46 arranged between the end members of the frame 1 and the head of the plunger 42.

The men 15 are positioned and arranged so that they will drive the puck away from the players. Referring to Fig. 3 of the drawings, the men 15 swing away from the players who control the levers and, therefore, when the levers are operated there is a drive toward the opponent's goal. This can be readily seen by an inspection of Figs. 2 60 and 3 of the drawings whereby the men 15 located at the positions A to H, inclusive, and controlled by their respective operating levers 27 will operate from a position toward the player at the left, Fig. 1, and swing upwardly and toward the 70 opponent. Likewise, the men 15 which are operated by the opponent to the right will cause the driving force to be exerted toward the opponent. The men 15 located at the positions K to R, inclusive, therefore, and controlled by their re- 75

spective operating levers 27 will operate from a position toward the player at the right, Fig. 1, and swing upwardly and toward the opponent.

The rubber top 32 has the positions of the men 15 indicated by spots, and the spots for opposing sides may be different colors. The spots locating the position of the players A to H, inclusive, may be red, while the spots indicating the position of the players K to R, respectively, may be blue. Therefore, each player knows the position of his men and when the puck gets near the position of the men each player knows which one of the members 27 to operate so as to not only prevent the opponent from forcing the puck toward his goal zone, but to also permit the player to force the puck away from his own zone toward the opponent's goal.

The playing surface 32 has a starting point indicated by the letter X, Fig. 1, and this starting point is located in the center of the playing field. The puck is therefore placed at the point X when the game is first started.

In playing the game the puck is located at the position X, Fig. 1, and is first operated by the player whose turn it is to play first. If, however, the player on the left starts play, he would probably operate the member 27F which, while not tending to move the puck toward the opponent's goal, would cause the puck to roll to the left into a position whereby it could be driven to the right toward the opponent's goal by the manipulation of the men indicated at the positions B, C, or D. The opponent, however, would naturally operate the man indicated at the position P and subsequently operate the members R, O, or Q so as to tend to force the puck into the opening 37. Should the opponent on the right, however, succeed in moving the puck near the goal 39, the player to the left, Fig. 1, would press the plunger 42, probably rapidly, with the hope that the part surrounding the openings 41 of the plate 40 would engage the puck and forcedly drive it to the opponent's goal, it being the object, of course, to manipulate the levers 27 so as to cause the ball or puck to roll or be driven always toward the opponent's goal. In such cases where the puck is not immediately over a man 15, the operation of a man 15 by the member 27 will cause the ball 20 of the man 15 to raise the playing surface, as shown in Fig. 5, and provide an inclination causing the ball to roll.

In referring to Fig. 4, the puck 38 is shown moving toward the right near the position of a man 15. The opponent, desiring to have the puck move the other way, will then operate a lever 27 to operate a man 15 so as to either strike the puck 38 or raise the surface, as shown in Fig. 5, to reverse the position of the puck toward the opponent's goal.

The game is exceedingly fast and interesting and creates considerable enthusiasm. If the rule of the game restricts the player from operating more than one man at a time, the game will harmonize more closely to hockey and makes the game still more interesting as the player must know which finger to operate when the puck arrives at a certain position so that the man in that particular position can be operated either to retard the opponent's advance or advance the puck toward the opponent's goal.

The sloping, inclined edges 36 tend to direct the puck toward the goal, while the side edge members 33 prevent the puck from becoming lodged along the edge, the strips 33 tending to fill

in the corners between the top playing field and the side edges.

The game has been described in connection with the association game of hockey but other games may be also played. The invention provides a fascinating, interesting game for use at home or other places, is rigid in construction, and can be economically manufactured. Certain of the parts are removable, such as the strips 33 and 34, so as to permit quick and easy removal or replacement of the playing surface 32. The end pieces 35 may also be removable so that easy access may be had to the levers, the goalie, and the spring connections.

The outward movement of the members 27 is limited by the leg 29, while the inward movement is limited by the members 34. These limits tend also to limit the movement of the striking element 20. However, to overcome any momentum and positively limit the upward movement of the striking element 20 a stop 47, Fig. 8, may be provided. This stop 47 is in the form of a cross bar connecting the legs 17.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. A game board comprising an open top frame, a sheet of elastic material extending over the top of the frame to form a playing surface adapted to support a freely movable element thereon, a plurality of vertically shiftable, longitudinally and laterally spaced balls within the frame forming men arranged in teams beneath, and spaced from, the playing surface, means at one end of the board for individually and selectively shifting the balls forming men of one team to cause said balls to strike the playing surface in a direction to impel said movable element across said surface generally in a direction toward the other end of the board and means at the other end of the board for individually and selectively shifting the balls forming men of another team to cause said balls to strike and distort the playing surface and impel said movable element across said surface toward said first end of the board, said balls being operatively connected to said shifting means for actuation thereby.

2. A game board comprising an open top frame, a sheet of elastic material over the top of the frame, and forming a playing surface adapted to support a freely rolling ball thereon, a plurality of vertically shiftable, longitudinally and laterally spaced striker balls within said frame forming men arranged in teams beneath, and spaced from, the playing surface, the men of one team being interspersed with the men of the other team, means forming goals at opposite ends of said surface, means adapted to be operated by one player for individually and selectively shifting the striker balls of one team to cause said striker balls to strike the playing surface in a direction to impel said freely rolling ball across said surface toward the goal of the opposing player, means adapted to be operated by said opposing player for individually and selectively shifting those striker balls forming men of the other team to cause said striker balls to strike and distort the playing surface and impel said freely rolling ball across said surface toward the goal of the first mentioned player, said striker balls being operatively connected to said shifting means for

- actuation thereby, and shiftable protective means associated with each goal, said protective means comprising a plate movably mounted on the playing surface and having an opening therein sufficient to permit the freely rolling ball on the playing surface to pass therethrough and into the goal, and means for shifting said plate sufficiently to prevent passage of the freely rolling ball through said opening.
3. A game board comprising an open top frame, a sheet of elastic material extending over the top of said frame to form a playing surface adapted to support a freely rolling ball, a plurality of angularly shiftable, longitudinally and laterally spaced balls forming striker elements arranged as men of opposing teams beneath, and spaced from, the playing surface, said game board having spaced openings forming goals at opposite ends of said playing surface, and means for individually and selectively operating said striker elements, said means comprising a plurality of individual flexible leads extending from the striker elements to the ends of the frame, a plurality of finger operated members at the ends of said frame and each being connected to one of said flexible leads, and means for normally urging said flexible leads in a direction to maintain each of said striker elements in an inoperative position, the finger operated members for the striking elements forming men of one team being disposed at one end of the board and the finger operated members for the striker elements forming men of the opposing team being disposed at the opposite end of the board, and means for mounting the balls so that the striker elements forming men of one team and the striker elements forming men of the opposing team strike the playing surface at oppositely directed angles whereby the men of one team impel the freely rolling ball generally toward one goal and the men of the other team impel said freely rolling ball generally toward the other goal.
4. A game comprising an open top frame, a sheet of elastic material extending over and closing the top of said frame to form a playing surface, a freely rolling ball on said surface, a plurality of longitudinally and laterally spaced striker elements within said frame and beneath the playing surface, indications on the playing surface of the positions of said men beneath the surface, pivotal supporting means for each of said striker elements, means for individually and selectively pivoting each of said striker elements on its pivotal supporting means, said means comprising a plurality of individually operating members extending from the striker elements to the ends of the frame, a plurality of finger operated members at the ends of said frame, each being connected to one of said operating members, the finger operated members for certain of said striker elements being disposed at one end of the frame and the finger operated members for the remaining striking elements being disposed at the

opposite end of the frame, means forming goals at opposite ends of the playing surface, shiftable goal protective means associated with each goal, said protective means comprising a plate having an opening therein of sufficient size to permit the freely rolling ball to pass therethrough and into the goal, and means for shifting said plate sufficiently to prevent the passage of the ball through said opening, the axis about which certain of said striker elements pivot being spaced from said elements toward the opposing goal and the axis about which the remaining striker elements pivot being displaced from said remaining striker elements toward the opposite goal whereby said striker elements impel the ball toward an opponent's goal.

5. A game comprising an open top frame, a sheet of elastic material extending over and closing the top of said frame to form a playing surface, a freely rolling ball on said surface, a plurality of longitudinally and laterally spaced striker elements within said frame and forming men arranged in teams beneath the playing surface, indications on the playing surface of the positions of said men beneath the surface, means for pivotally supporting each of said striker elements, means for individually and selectively operating each of said striker elements about its pivotal support, said means comprising a plurality of individual, flexible leads extending from the striker elements to the ends of the frame, a plurality of finger operated members at the ends of said frame and each being connected to one of said flexible leads, and spring means for normally urging said flexible leads in a direction to maintain each of said striker elements in an inoperative position, the finger operated members for those striker elements forming men of one team being disposed at one end of the frame and the finger operated members for those striker elements forming men of the opposing team being disposed at the opposite end of the frame, means forming goals at opposite ends of the playing surface, shiftable goal protective means associated with each goal, said protective means comprising a plate having a plurality of spaced openings therein each of sufficient size to permit the freely rolling ball to pass therethrough and into the goal, and means for shifting said plate sufficiently to prevent passage of the ball through said openings, the pivot axes of the striker elements forming men of one team being spaced from said elements toward the opposing goal, the pivot axes for the striker elements forming men of the opposing team being displaced from the striker elements toward the opposite goal and each of said striker elements having a convex upper surface portion whereby said striker elements when operated form convex projections in the playing surface to impel said ball laterally and longitudinally of the playing surface and generally toward an opponent's goal.

JOHN L. ZINNGRABE.
